SIGNORS TO NATIONAL ENAMELING & STAMPING CO., INC., OF MILWAUKEE, WIS-
CONSIN.

LIQUID-FUEL HEATING STOVE.

Application filed December 1, 1927. Serial No. 237,004.

Our invention refers to vapor burning stoves, and it has for its object to provide a simple, economical and effective means for temporarily locking a removable fuel tank and associated parts to the burner and body of the stove.

We are aware of the fact that in this general type of stove it is common practise to remove the fuel reservoir and associated parts, and in so doing various types of brackets or supports have been provided for the removable unit, whereby said unit must be more or less definitely alined and moved, or slid into position upon track members.

15 This common arrangement has been found to require more or less fine adjustment and accuracy in manipulation when the unit is inserted—otherwise, a binding effect is produced.

20 Our invention contemplates further the provision of a simple mechanism for accomplishing the locking feature of the removable unit, whereby cost of production is materially lessened.

25 With these general objects in view, the invention primarily contemplates an arrangement whereby the vapor tube, constituting a part of the reservoir unit, is inserted into the burner from the front of the stove body, and thereafter a fin-lock at the opposite end of the unit is effected to prevent movement or swinging of the unit with relation to the burner connection.

With the above and other minor objects 35 in view, the invention consists in certain peculiarities of construction and combination of parts, as will be hereinafter set forth with reference to the accompanying drawings and subsequently claimed.

40 In the drawings:—

Figure 1 represents a front elevation of a stove embodying the features of my invention, with parts in section, as indicated by line 1—1 of Figure 2.

45 Figure 2 is a cross sectional elevation, the section being indicated by line 2—2 of Figure 1, it being understood that only such fragmentary parts of the stove are illustrated to define the application of our invention to the same.

50 Referring by characters to the drawings, 1—1' indicate the side panels of a stove body, 2 the back panel thereof, and 3, the bottom panel. Secured to the end panels 55 of the stove body is a standard burner head

4 of the manifold type having a plurality of tips 5—5' extending therefrom, which tips in practise are adapted to have associated therewith the usual radiant elements. The rear panel of the stove has suitably fitted thereto a fire-clay back wall 6. The manifold, which is of standard type, is provided with a forwardly extended burner section 7, which communicates with the manifold section, said burner section having a vapor inlet orifice 8, and an air intake mouth 9, as best shown in Figure 1.

All of the stove parts, as above explained and illustrated, are of standard type and form no part of the invention.

Removably supported upon the base or bottom 3 of the stove is a fluid fuel reservoir 10 having a pair of foot brackets 11—11' secured thereto, which brackets rest upon the flat surface of the bottom 3. The tank is provided with the usual cap filling opening 12 and valve controlled feed pipe 13, which feed pipe communicates with a valve-controlled generator tube 14 that is arranged above and parallel with the reservoir. The generator tube is supported by brackets 15—15', which brackets are permanently connected to the reservoir and also serve as supports for a drip pan 16 which is positioned directly under the generator tube.

The side panel 1' of the stove body is formed with a comparatively large aperture 1'' through which the generator tube and its associated valve handle 17 are arranged to be passed through when the reservoir unit is assembled in position for functioning. As best shown in Figure 2 of the drawings, the open front of the stove body is preferably provided with a hinged front panel 18, which front panel is swung upwardly from the position shown in Figure 2 when the removable reservoir unit is in its working position, it being understood that this front panel is swung downwardly in the position shown in Figure 2 when it is desired to remove the said unit.

It will be noted that the burner 7, preferably of the Bunsen type, is positioned near one of the end panels, and when it is desired to insert the reservoir unit there is ample end play between the side panels of the stove body, whereby the said unit can be inserted through the front opening of said stove body, while at the same time the

valve wheel 17, and its associated parts, is inserted through the opening 14 of the panel 1'. In this position the feet of the reservoir 11-11' rest solidly upon the flat bottom 3, and thereafter the discharge end 14' of the generator tube is moved towards the burner orifice 8 and inserted therein, as shown in Figure 1. This lateral movement, to effect the locking engagement between the generator discharge end and burner orifice, is limited by the bracket 15', which abuts the juxtaposed end wall of the burner.

After this interlocking connection between the removable unit and the stove burner is effected, parallel alinement of the removable unit and the burner is accomplished by a cam indenture 19, which is formed in the bottom 3. This indenture having conical or tapered walls, is provided to be engaged by a conical head 20 of a spring-controlled locking dog 21, which locking dog is pivotally mounted upon the reservoir supporting foot 11'.

Hence, it will be seen that the reservoir unit is supported by its end and is secured in its functioning position by the interlocking connection between the burner and the manifold at one end, and an interlocking connection between the spring controlled dog and the cam indenture 19 at the other end of the stove. Owing to this simple means of temporarily anchoring the removable unit, said removable unit can be quickly assembled or extracted from the stove for filling or repair purposes, and in so doing it will be observed that no particular accuracy or fine adjustment are necessary to manually effect the working connection between the said movable reservoir unit and the fixed stove parts.

While we have shown and described a simple exemplification of our invention, it is understood that we may vary the structural features of it within the scope of the claims.

We claim:

1. A stove body having a burner provided with a vapor inlet at one end and a removable fluid reservoir unit having a generator tube adapted to engage and interlock with the vapor burner inlet, and means carried by the reservoir for a second interlocking engagement with a stove body at a point remote from the first mentioned interlocking mechanism. 45

2. A stove body having a burner provided with a vapor inlet and a removable fluid reservoir unit having a generator tube carried thereby for interlocking engagement, supporting feet extending from the reservoir adapted to rest upon the bottom of the stove body, and movable means carried by said reservoir for interlocking engagement with said stove body. 50

3. A stove body having a burner provided with a vapor inlet aperture, a removable fluid reservoir having a vapor tube in communication therewith, the same being provided with a discharge end adapted to engage the burner inlet orifice, supporting feet for the reservoir arranged to rest upon the bottom of the stove body, the said stove body bottom having an indenture therein, and a dog carried by the reservoir for engagement with the indenture. 55

In testimony that we claim the foregoing we have hereunto set our hands at Milwaukee in the county of Milwaukee and State of Wisconsin. 70
